DESIGN FOR A SHOE

Jacob Sandler, Brookline, Mass.

Application November 22, 1934, Serial No. 54,119

Term of patent 7 years

To all whom it may concern:

Be it known that I, Jacob Sandler, a citizen of the United States, residing at Brookline, in the county of Norfolk and State of Massachusetts, have invented a new, original, and ornamental Design for a Shoe, of which the following is a specification, reference being had to the accompanying drawing, forming part thereof, in which:

Fig. 1 is a top plan view and Fig. 2 is a view in side elevation of a shoe showing my new design.

I claim:

The ornamental design for a shoe as shown. In testimony whereof, I have signed my name to this specification.

JACOB SANDLER
